UNITED STATES PATENT OFFICE

139,807

DESIGN FOR A DART GAME BOARD

Henry Elton Pease, Chicago, Ill., assignor to Henry C. Hitzeman, Clarence B. Winkler, and
Henry Elton Pease, all of Chicago, Ill.

Application October 15, 1943, Serial No. 111,387

Term of patent 14 years

(Cl. D34—5)

To all whom it may concern:

Be it known that I, Henry Elton Pease, a citizen of the United States residing at Chicago, in the county of Cook and State of Illinois, have invented a new, original, and ornamental Design for a Dart Game Board, of which the following is a specification, reference being had to the accompanying drawing, forming a part thereof.

In the drawing:
Fig. 1 is a front elevational view of a dart game board showing my new design, and
Fig. 2 is an edge view thereof.

I claim:
The ornamental design for a dart game board, as shown.

HENRY ELTON PEASE.
